HAND HELD BLOCKING DUMMY

Harold W. Kopp, 21 Lancaster Drive,
Saxonville, Mass. 01523

Filed Nov. 8, 1974, Ser. No. 522,015

Term of patent 14 years

Int. Cl. D21—02

U.S. Cl. D34—5 K

FIG. 1

FIG. 2

FIG. 3

FIG. 4

FIG. 1 is a front elevational view of a hand held blocking dummy showing my new design;

FIG. 2 is a side elevational view thereof;

FIG. 3 is a rear elevational view; and

FIG. 4 is a top plan view.

I claim:

The ornamental design for a hand held blocking dummy, substantially as shown and described.
